[57] ABSTRACT

A fluid-distribution device that includes a body defining a cylindrical chamber complementarily receiving a rotatable spool, the interior of which is divided into two passageways, the first having an inlet adapted to receive fluid and a restricted outlet, the second having an outlet which along with the outlet of the first passageway is directed to the discharge opening for the body. The body also is provided with sets of pairs of openings leading to containers adapted to receive material to be introduced into the fluid. An opening in the spool for each of the passageways provides a set of openings selectively alignable with the pairs of openings leading to the containers for thereby diverting water from the first passageway through the selected container and back into the second passageway for discharge.

FLUID-DISTRIBUTION DEVICE

BACKGROUND OF THE INVENTION

1. Field of the Invention

This invention pertains to a fluid-distribution device particularly adapted to divert water to selected containers for dissolving material therein

2. Description of Prior Art

It has been recognized that in a shower bath it is advantageous to be able to introduce substances into the water. This may be, for example, soap, shampoo, lotion, oil or the like. However, there has been no fully satisfactory means for mixing such substances into the water. One proposal included an elongated manifold having a water inlet and a restricted outlet, with various containers attached to the manifold, each with a substance to be introduced into the water. An individual valve control was provided for each of the containers to cause the water to flow into selected ones for dissolving material therein and conducting it to the shower head. This device was quite bulky and relatively expensive. It was not simple to operate in view of the multiplicity of valve controls. Also, the various valves could be left open inadvertently, there being no assurance that only one of the containers was open at a time.

Additional prior designs are shown in U.S. Pat. Nos. 2,215,000, 2,562,415, 2,602,697 and 3,349,788, each providing only a single chamber for retaining material to be dissolved in the water. In U.S. Pat. No. 2,120,774, two chambers are included, but the valve provides equal flow through both.

SUMMARY OF THE INVENTION:

The present invention provides an improved attachment for a shower bath, which allows appropriate materials to be mixed into the water, while being a compact and low-cost unit that is simple and foolproof to operate. The device includes a body that defines a cylindrical chamber which rotatably receives a spool that is controlled by an external knob. The spool is longitudinally split internally to define two passageways. The first passageway has a relatively large inlet opening at one end and a relatively small outlet opening at the opposite end providing a restriction so that there is a buildup of pressure within the first chamber. The second passageway also has an outlet opening at the opposite end, both of the outlet openings communicating with an annular groove in the exterior of the spool, which, in turn, is connected to the outlet pipe that goes to the shower head. The shower head should provide aeration of the water.

In the intermediate portion of the body, there are outlets leading to various containers, which are adapted to receive the material to be dissolved and picked up by the water. For each of these containers, there are two openings through the wall of the body. The spool includes an opening for the first passageway and an opening for the second passageway, which are selectively registerable with the two openings for each of the containers. When so aligned with the openings for the containers, some of the water from the first passageway will flow through one set of aligned openings into the container to dissolve the material, which then discharges from the other set of aligned openings into the second passageway to be conducted to the outlet and directed to the shower head. The

material in the containers is retained in lightweight disposable packages, which are reinforced by the containers that provide the structural attributes to withstand the pressure of the water. The containers are removable for replacement of the material to be dissolved.

While being particularly adapted for use in a shower bath, the fluid-distribution arrangement of this invention is usable in other instances where it is desired to divert a stream of fluid into selected containers.

BRIEF DESCRIPTION OF THE DRAWING:

FIG. 1 is an end elevational view of the fluid-distribution device of this invention;

FIG. 2 is a side elevational view of the device;

FIG. 3 is a sectional view taken along line 3-3 of FIG. 2;

FIG. 4 is a sectional view taken along line 4-4 of FIG. 3;

FIG. 5 is a sectional view taken along line 5-5 of FIG. 3; and

FIG. 6 is a fragmentary view similar to the central portion of FIG. 3, but illustrating the spool in a different rotational position.

DESCRIPTION OF THE PREFERRED EMBODIMENT:

The device 10 of this invention is illustrated in FIGS. 1 and 2 in association with a conventional shower bath arrangement, positioned upstream of the shower head 11. The device 10 includes a tubular body 12 which at one end 13 is enlarged and internally threaded to mate with an end closure member 14. The latter member includes an opening 15 that receives the end of a pipe 16 which brings water into the device 10. The pipe 16 extends outwardly from the wall in the usual manner for shower baths and is downstream of the hot and cold water valves (not shown).

The body 12 and the member 14 collectively define a cylindrical chamber 18 which substantially complementarily receives a hollow spool 19. One end wall 20 of the spool 19 is adjacent a radial end wall 21 of the body 12, while the opposite end 22 of the spool is adjacent an annular shoulder 23 at the end of the chamber 18. The shoulder 23 and the end wall 21 position the spool 19 against axial movement. The spool 19 is rotatable, however, having a stem 25 that extends outwardly through an opening 26 in the body end wall 21, with a knob 27 being received on the stem to effect rotation.

An internal longitudinal wall 29 runs the full length of the spool 19 between its end walls 20 and 22 as well as extending diametrically across the width of the spool. This forms a partition that divides the interior of the spool into two passageways 30 and 31. A relatively large inlet opening 32 in the end wall 22 provides access to the chamber 30 of the spool 19. Adjacent the opposite end of the spool 19 is a smaller outlet opening 33 for the chamber 30. Diametrically opposite from the opening 33 is an outlet 34 for the other chamber 31. The openings 33 and 34 communicate with an annular groove 35 in the exterior circumferential surface of the spool 19, which, in turn, connects to an outlet opening 36 in the body 12. A pipe 37 is received in the opening 36 and connects to the shower head 11. O-rings 38 and

39 fit in small annular grooves 40 and 41 in the spool 19 on either side of the annular groove 35 to isolate the discharge end of the spool. There is, in addition, an O-ring 42 in an annular groove 43 sealing the end of the spool adjacent the wall 22.

Projecting radially outwardly from the central portion of the body 12 are four short tubular elements 45, 46, 47 and 48 which are equally spaced apart angularly. For each of these elements there is a pair of spaced openings extending radially through the body 12. These are the openings 49 and 50 for the tubular section 45, 51 and 52 for the tubular section 46, as well as the openings 53 and 54 for the tubular element 47, and openings 55 and 56 for the tubular part 48. At the outer ends of the tubular sections 45, 46, 47 and 48 are connected tubular enlargements 58, 59, 60 and 61, each of which includes a radial wall and a short externally threaded cylindrical portion. These are engaged by cylindrical canisters 62, 63, 64 and 65, which are closed at their outer ends. Within these canisters are lighter containers, which may be of plastic material, such as the container 66 shown for the canister 62. These containers are complementary to the interiors of the canisters. The container 66 is open at its inner end and contains a water-soluble product 67, normally in solid form. Typically, this will be a material useful in the bath, such as soap, oil, shampoo or lotion. Ordinarily, there is a different water-soluble substance in each of the canisters 62, 63, 64 and 65.

On either side of the wall 29 and immediately adjacent to it are radial openings 69 and 70 through the circumferential wall of the spool. The openings 69 and 70 fall in the same radial plane as the openings 49 through 56 in the body 12. The opening 69 communicates with the chamber 30, while the opening 70 connects to the chamber 31. The spacing between the openings 69 and 70 is the same as that between each pair of openings through the body 12 at the outwardly projecting tubular sections 45, 46, 47 and 48. Consequently, the openings 69 and 70 may be positioned adjacent the solid portion of the wall of the body 12 as in FIG. 3 or, by rotation of the knob 27, may be placed in registry with any pair of openings through the body. In FIG. 6, for example, the openings 69 and 70 are aligned with the openings 50 and 49, respectively, through the wall of the body 12. O-rings 78 and 79, recessed in the circumferential wall of the spool 19, circumscribe the openings 69 and 70, respectively, providing seals at those locations.

When the shower is in operation, water from the inlet pipe 16 enters the outer end portion of the chamber 18 upon first passing through a cylindrical screen 71. The latter element is removable for cleaning by loosening a screw 72. Upon leaving the cylindrical filter screen, the water then enters the chamber 30 by flowing through the inlet opening 32 in the wall 22. When the spool 19 is in the position of FIG. 3, with the openings 69 and 70 adjacent the solid portion of the wall of the body 12, the water can flow from the chamber 30 only through the outlet opening 33, which directs it into the annular groove 35. The water then is conducted through the outlet opening 36 into the pipe 37 that leads to the shower head 11.

If it is then desired to introduce into the water material from one of the canisters, the knob 27 is

turned so as to align the openings 69 and 70 with the openings in the body 12 that lead to the desired canister. Suitable indicia may be provided to assure correct alignment of the openings 69 and 70, such as, for example, the pointer 73 on the knob 27 and the indexing marks 74, 75, 76 and 77 on the tubular sections 45, 46, 47 and 48, respectively. When the spool 19 is positioned, for example, as shown in FIG. 6, with the openings 69 and 70 in registry with the openings 50 and 49, respectively, a portion of the water from the chamber 30 will be caused to flow outwardly through the openings 69 and 50 to enter the container 66 within the canister 62. This flow of a portion of the water occurs because the outlet opening 33 for the chamber 30 is smaller in diameter than the inlet opening 32. As a result of this constriction, pressure builds up within the chamber 30 so that water is forced outwardly through the opening 69.

The water flowing through the aligned openings 69 and 50 will circulate through the canister where it will contact the material 67 within it, dissolving a portion of this material. The water then is forced through the outlet provided by the aligned openings 70 and 49. This directs the water from the canister 62 into the chamber 31 of the spool 19. The flow is then to the end of the chamber 31, where the water discharges through the outlet opening 34 into the annular groove 35. This water, bearing the dissolved material from the canister 62, mixes with the remainder of the water which has been conducted longitudinally through the chamber 30 to its outlet opening 33. Consequently, the water discharged from the pipe 37 through the shower head 11 contains some of the material, such as soap, oil, shampoo, lotion or the like, which was held in the canister 62.

It is a simple matter to change the setting of the spool 19 so as to introduce into the water material from any of the canisters. The knob 27 simply is rotated so as to align the openings 69 and 70 with the two apertures that communicate with each of the canisters selected. Thus, the device of this invention readily provides for introducing dissolved material into the water, or as easily causing the water to flow directly through the spool without contact with any of the material. When one canister is selected, the others automatically are shut off and receive no flow of water.

When the contents of any of the canisters become exhausted, it is very simple to provide a new supply. The inner container 66 and the material to be dissolved 67 may be provided as a cartridge that is slipped into place after the canister is unscrewed from its mounting. The wall of each canister reinforces the inner container 66 so that the latter may be made very economically from lightweight material.

The foregoing detailed description is to be clearly understood as given by way of illustration and example only, the spirit and scope of this invention being limited solely by the appended claims.

I claim:

1. A device for selectively introducing material into a fluid comprising
a body defining a chamber,
a member in said chamber,
said member having a first passageway and a
second passageway therein,

an inlet means for said first passageway for receiving a fluid,
 an outlet means for each of said first and second passageways,
 said outlet means for said first passageway providing a constriction relative to said inlet means,
 a plurality of containers adapted to receive material to be introduced into fluid,
 a duality of opening means in said body communicating with each of said containers,
 an opening means in said member for each of said passageways,
 and means for selectively positioning said opening means of said member in communication with said duality of opening means for each of said containers such that said opening means for said first passageway communicates with one of said duality of opening means for one of said containers and said opening means for the other of said passageways communicates with the other of said duality of opening means in said body for said one container.

2. A device as recited in claim 1 in which said chamber is cylindrical, said member has a cylindrical exterior substantially complementarily received in said chamber, and said means for selectively positioning said opening means includes means for rotating said member relative to said body.

3. A device as recited in claim 2 in which said body has an outlet communicating with said outlet means for said first passageway and said outlet means for said second passageway for discharging fluid therefrom.

4. A device as recited in claim 3 including in addition fluid conduit means one end of which is connected to said outlet of said body, and a shower head connected to the opposite end of said fluid conduit means for discharging fluid therefrom.

5. A device as recited in claim 4 including a second container complementarily received in each of said first-mentioned containers, and a water-soluble material in each of said second

containers, said second containers being supported externally by said first-mentioned containers.

6. A device as recited in claim 5 in which said first-mentioned containers are removable for allowing replacement of said second containers.

7. A device as recited in claim 3 in which said body is provided with a plurality of radially projecting sections, each of said radially projecting sections having a duality of said opening means in said body, said containers being carried at the outer ends of said radially projecting sections.

8. A device as recited in claim 7 in which there are four of said radially projecting sections and four of said containers.

9. A device as recited in claim 2 in which said member includes a longitudinally extending diametrical wall dividing said member so as to provide said first and second passageways.

10. A device as recited in claim 9 in which said opening means for said first passageway is a radial opening through the circumferential wall of said member adjacent one edge of said wall on one side thereof, and said opening means for said second passageway is a radial opening through said circumferential wall of said member adjacent said edge of said longitudinal wall and on the opposite side thereof.

11. A device as recited in claim 2 including in addition indicia exteriorly of said body for indicating the rotational position of said member within said body.

12. A device as recited in claim 2 in which said member includes an end wall, said inlet means for said first passageway being in said end wall.

13. A device as recited in claim 2 in which said member includes an annular groove in the external surface thereof, said outlet means for said first passageway and said outlet means for said second passageway communicating with said annular groove, said body having an outlet communicating with said annular groove for discharging fluid therefrom.
